BABY JUMPER

Thomas H. Mekeel and Leland L. Cammack,
San Jose, Calif.

Application April 16, 1956, Serial No. 578,250

7 Claims. (Cl. 155—18)

This invention relates to a so-called baby jumper which is adapted for use by comparatively young children.

Jumpers of the character described are known in the art, and comprise a seat frame for supporting a baby seat at one end, being pivotally mounted for rocking movement intermediate its ends, and held by resilient means at the opposite end so that the baby may amuse himself by rocking the seat frame against the action of the resilient means.

Summarizing this invention, it has as its objects, among others, the provision of an improved jumper of the character described which is composed of few and simple parts, thus making for economy of manufacture, is portable and collapsible whereby it can be folded into a compact space wherein all the parts lie in substantially the same plane, thus facilitating storage and handling, and which is of such construction enabling the baby seat to be readily removed for cleaning and replacement after it has become soiled through usage by the baby.

Referring to the drawings:

Fig. 1 is a side elevational view of the jumper in erected position;

Fig. 2 is an isometric view;

Fig. 3 is an elevational view illustrating the manner in which the jumper can be collapsed;

Fig. 4 is a plan view illustrating the arrangement of the parts with the jumper in collapsed state; portions of the structure being broken away to disclose the construction more clearly.

The jumper comprises a base frame 2 desirably of generally rectangular shape and formed of light metal tubing, to thus provide an open frame construction. Pivotally connected at 3 to side members 4 of the base 2 are a pair of support members 6; such support members being connected to the base frame adjacent the front end thereof a little less than a third of the length of such base frame. Mounted for detachable pivotal movement on support members 6 is a generally U-shaped baby seat frame 7 closed at one end 8 and open at the opposite end 9; the side legs 11 of such seat frame being displaced inwardly from adjacent the open end of the seat frame for a purpose to be later described. Frame 7 is desirably of light tubing.

For providing such detachable pivotal connection of the seat frame, a support rod 12 having a head 13 (Fig. 4) at one end passes through apertures 14 in the upper end of support members 6 and through apertures 16 in legs 11 of the seat frame. When the seat frame is mounted on the support members 6, a wing nut 17 screwed on rod 12 opposite to the head end 13, holds the entire assembly together. At the same time, seat frame 7 can rock or pivot about rod 12 in the upright position of support members 6.

With reference to Figs. 1 and 4, it will be noted that the seat frame 7 is of less length than base 2 and is also of less width, so that it can fit within the open area of base 2; and the seat frame is pivoted adjacent its front

2

end at a point about one-fourth the length of such seat frame.

For holding support members 6 in an upright position and the seat frame 7 in an elevated position, strut means 18 is connectable between such support members 6 and base 2; the strut means extending rearwardly from the support members to base 2. Such strut means may be a pair of relatively stiff rod members detachably connectable to the described parts when the seat frame is erected. 10 However, in the embodiment illustrated, each strut means comprises a link 19 pivotally connected to an upright support member 6 and also pivotally connected at 20 to another link 21, in turn pivotally connected to base 2. Each link 21 has a pin 22 adapted to engage in a slot 23 15 in the associated link 19 in the set up position of the seat frame.

A special type of baby seat 26 is removably mounted on the closed end 8 of seat frame 7. This seat is desirably formed of any suitable strong flexible and washable material, such as plastic or cloth and at its upper end is provided with a looped portion 27 formed by a hem. Desirably, an apron portion 28 is provided to extend upwardly from the bottom of the seat. Loop portion 27 readily permits the seat to be removed from 25 the open end of the seat frame for cleaning or washing, and also to be readily replaced.

Because of the open end 9 of the seat frame which permits ready removal and replacement of baby seat 26, its legs 11 have a spring effect; and detachable spacer means is provided between legs 11 of the seat frame to hold such legs in position when wing nut 17 is tightened. Such spacer means includes a front spacer rod 31 30 removably insertable into apertures formed in the inner sides of legs 11; the ends of rod 31 being adapted to 35 abut against unapertured outer sides of such legs. Thus, when the baby seat is to be removed, spacer rod 31 can be readily removed after the seat frame is detached from pivot rod 12. Reassembly of these parts can be quickly effected in a reverse manner.

At the other side of pivot rod 12 is also provided a pair of spacer rods 32 mounted similarly to spacer rod 31. Spacer rods 32 are adapted to pass through looped portions 33 formed by hems in the apron portion 28 of the seat, which includes an apron extension 34 to provide 40 a shelf in which the baby may place toys or the like. Rods 32 can be removed and replaced in the same manner as rod 31.

With reference to Fig. 4, it will be noted that the inward displacement of the seat frame legs 11 provides a 45 space between each leg 11 and a base frame side member 4 in the collapsed position of the jumper, to thus accommodate support member 6 within such space in the collapsed position of the jumper. The upper ends of the support members 6 are also displaced inwardly to facilitate pivotal connection with the inwardly displaced portion of legs 11.

To complete the assembly, resilient means is provided 50 for detachable connection between the front end of the seat frame opposite the baby seat and the front end of the base frame. Such resilient means comprises coil spring means 36 having an eye 37 at its upper end connected over a bowed portion 38 on front spacer rod 31, and a hook 39 at its lower end detachably connectable in an aperture or similar attaching means on the front 55 end of base 2. Desirably, the coil spring means 36 is formed of coil spring sections of different diameters with section 41 of lesser diameter screwed into section 42 of larger diameter. Such arrangement provides means for adjusting tension of the spring in accordance with the 60 weight of the baby.

In collapsing the jumper, this can be readily done by unhooking hook 39 of spring means 36, and turning sup-

port members 6 in one direction rearwardly as indicated by the direction arrow D in Fig. 3, and simultaneously turning seat frame 7 in an opposite direction forwardly as indicated by direction arrow D'. This enables the jumper to be collapsed with the seat frame lying within the open area of the base frame and substantially in the same plane thereof, so that it can be very readily transported. Setting up of the jumper can be readily accomplished in a reverse manner.

When the jumper is set up, it will be noted that the length of seat frame 7 is such that it does not substantially overhang the ends of base frame 2 and the sides of the seat frame are located between the sides of the base frame. This, in cooperation with the rectangular shape of the base frame, provides for great stability in use. Only one element, namely wing nut 17, need be unscrewed when it is desired to remove seat 26 for cleaning. Hence, disassembly of the seat frame can be quickly effected. When the wing nut is unscrewed and support rod 12 pulled out, rods 31 and 32 are readily removed from legs 11 of the seat frame. Rods 32 can be quickly removed from seat 26 by sliding them out of loops 33 formed in the apron portion 28, and the seat can be quickly removed by sliding it off either of legs 11. Since only one wing nut 17 holds the entire seat frame assembly together, reattachment of the parts can be quickly and easily effected.

We claim:

1. A portable collapsible baby jumper comprising an open base frame adapted to rest on a support, a seat frame of a size adapted to fit within the confines of said base frame, support members pivotally connected to each of said frames and turnable in one direction from an upright position to a position adjacent said base frame, the seat frame being turnable in an opposite direction for positioning within said base frame, strut means connectable between said support members and said base frame for holding the support members upright with the seat frame in an elevated position, a baby seat supported adjacent one end of said seat frame, and means adjacent the opposite end of said seat frame providing attachment for resilient means adapted to be secured to said base frame.

2. A portable collapsible baby jumper comprising an open base frame adapted to rest on a support, a U-shaped seat frame having side legs, an open end and a closed end, said seat frame being of a size adapted to fit within the confines of said base frame, support members pivotally connected to said base frame and turnable in one direction from an upright position to a position adjacent said base frame, detachable means including a rod extending through the side legs of said seat frame and removable therefrom providing a pivotal connection of said seat frame with said support members, said pivotal connection enabling the seat frame to be turned in an opposite direction from said support members for positioning of said seat frame within said base frame, strut means connectable between said support members and said base frame for holding the support members upright with the seat frame in an elevated position, a baby seat of flexible material having a looped portion by which said seat is supported on the closed end of said seat frame, said looped portion enabling said seat to be removed from said seat frame by sliding it off a leg of the seat frame adjacent said open end, a spacer rod detachably connected between the legs of said seat frame adjacent the open end of said seat frame, and resilient means detachably connectable between said seat frame adjacent its open end and the base frame.

3. The jumper of claim 2 in which each of said legs has a portion displaced inwardly from adjacent the open end of said seat frame to provide a space between such

inwardly displaced leg portion and a side of said base frame in the collapsed position of the jumper, and each of said support members is shaped to lie within such space in the said collapsed position.

- 5 4. The jumper of claim 2 in which another spacer rod is detachably connected between the legs of said seat frame adjacent the closed end of said seat frame, and said baby seat includes an apron portion removably looped on said another spacer rod.
- 10 5. A portable collapsible baby jumper comprising an open base frame having a pair of spaced apart side frame members and a pair of spaced apart transversely extending end frame members, a seat frame having a length less than the distance between said end frame members 15 and a width less than the distance between said side frame members so as to fit within the confines of said base frame, support members pivotally connected to said side frame members and to the sides of said seat frame and turnable in one direction from an upright position to a 20 position within said base frame, the seat frame being turnable in an opposite direction for positioning within said base frame, strut means connectable between said support members and said base frame for holding the support members upright with the seat frame in an elevated position, a baby seat supported adjacent one end of said seat frame, and means adjacent the opposite end of said seat frame providing attachment for resilient 25 means adapted to be secured to said base frame.

6. The jumper of claim 5 in which said base frame is 30 of substantially rectangular shape to provide stability, said seat frame is substantially U-shaped and has side legs, an open end, and a closed end, and each of said side legs has a portion displaced inwardly from adjacent the open end of the seat frame to provide a space between such inwardly displaced leg portion and a side frame member of said base frame in the collapsed position of the jumper whereby in said collapsed position each of said support members is accommodated between a side frame member and an inwardly displaced leg 40 portion.

7. A portable collapsible baby jumper comprising an open base frame adapted to rest upon a support and including a pair of spaced apart side frame members providing an open space therebetween, a seat frame adapted 45 to fit within the confines of said base frame in the space between said side frame members, said seat frame including a pair of opposite sides, support members pivotally connected between the side members of said base frame and the sides of said seat frame and turnable in one direction from an upright position to a position adjacent the respective side frame members of said base frame, the seat frame being turnable in an opposite direction for positioning within said base frame with each 50 support member located between a side member of said base frame and a side of said seat frame, strut means connectable between said support members and said base frame for holding the support members upright with the seat frame in an elevated position, a baby seat supported adjacent one end of said seat frame, and means 55 adjacent the opposite end of said seat frame providing attachment for resilient means adapted to be secured to said base frame.
